Inventor
DAVID G. DOWNS

By Watson E. Coleman

Attorney

UNITED STATES PATENT OFFICE.

DAVID GRIFFIN DOWNS, OF ESTHERVILLE, IOWA, ASSIGNOR OF ONE-HALF TO GEORGE E. GROVES, OF ESTHERVILLE, IOWA.

PROJECTILE.

1,229,421.

Specification of Letters Patent. Patented June 12, 1917.

Application filed December 24, 1915, Serial No. 68,548. Renewed March 21, 1917. Serial No. 156,462.

To all whom it may concern:

Be it known that I, DAVID G. DOWNS, a citizen of the United States, residing at Estherville, in the county of Emmet and State of Iowa, have invented certain new and useful Improvements in Projectiles, of which the following is a specification, reference being had to the accompanying drawings.

10 This invention relates to projectiles and more particularly to a projectile of that general type known as a chain or cable shot, the invention having for its primary object to provide a device of this character which, 15 when projected from a gun or mortar, will have an active destructive influence over a wide area.

It is a more particular object of the invention to provide a projectile embodying 20 a plurality of metal balls each having a swivel connection to a wire cable or chain, and a spirally coiled section in the cable length adapted to unwind in the flight of the balls when discharged from the gun 25 muzzle.

The invention has for an additional general object to provide a projectile which may be advantageously employed for various purposes frequently encountered in 30 modern warfare, the device being highly effective in practical use and operating to quickly disseminate the ranks of the enemy.

With the above and other objects in view, my invention consists in the novel features 35 of construction, combination and arrangement of parts to be hereinafter more fully described, claimed and illustrated in the accompanying drawings, in which,

Figure 1 is an elevation, partly in section, 40 illustrating one form of my improved multiple projectile;

Fig. 2 is a side elevation showing an alternative mounting or arrangement of the coiled cable;

Fig. 3 is a plan view showing the arrangement of the device in connection with a multiple-barreled gun from which the same is to be discharged;

Fig. 4 is an elevation of another modification of the invention;

Fig. 5 is a view showing a further alternative form of the projectile;

Fig. 6 is a view illustrating the device equipped with drag hooks for destroying 55 barbed wire obstructions; and

Figs. 7, 8 and 9 are views illustrating several different methods of providing the projectile with illuminating means.

Referring in detail to the drawings, and more particularly to Fig. 1 thereof, 5 designates a series of solid balls or shot which may be of spherical or elliptical form, and each of these shot is provided with a swiveled ball bearing cap 6. As illustrated, three of the shot are employed, and the cap 6 of the central shot is provided with a housing 7 to contain the spirally wound medial portion of a cable 8. This central portion of the cable is doubled upon itself and then coiled into a spiral, the cable at the bend 70 therein which is located at the base of the coil being suitably fixed to the central rod 10 arranged in the housing 7. The cable extends in relatively opposite directions from the coils which are indicated at 9, 75 through suitable openings provided in the wall of the housing 7, and to the extremities of the cable one of the ends of the coil springs 11 are connected, the other ends of said springs being suitably 80 attached to the swiveled cap 6 of the other ball shots 5.

As shown in Fig. 2 of the drawings, if desired the central shot 5 may be eliminated, and the spirally wound coils in the central portion of the connecting cable 8 arranged upon the stationary conical reel 12, the coils in the cable being gradually reduced in diameter from the base of the reel to the apex thereof. Again, as shown in Fig. 3 of the drawings, the central portion of the cable may simply be coiled and arranged upon a suitable support indicated at S which projects forwardly between spaced diverging barrels B of the gun G, whereby the projectile is discharged.

In either of the three arrangements of the coiled cable above referred to, it will be manifest that when the shot is discharged from the gun or mortar, in the flight thereof the central coiled section of the cable will gradually unwind so that the distance between the connected shot balls will correspondingly increase. It is thus obvious that, by the time the projectile reaches its objective, the balls will have spread apart and the cable will be stretched taut so that the same will sweep over a large area and carry with it all obstructions in its path. The barrels of the gun, illustrated in Fig. 3, are 105 110

of course elevated in accordance with the range, and the explosive charges are ignited and exploded at the same time so that the balls will be discharged from the gun barrel 5 simultaneously and in divergent directions, thereby causing the coiled portion of the cable to immediately unwind.

In Fig. 4 of the drawings, I have illustrated a type of the device wherein the several ball shot are connected by springs or other yieldable elements with cable sections indicated at 13, the spiral coil above referred to being dispensed with. Upon the cable sections 13, a number of explosive bombs 14 are suitably attached, and from each cable section a flexible wire frame 15 depends, and upon the wires thereof suitable weights, indicated at 16, are fixed. These weights serve as small shot and have 20 a very destructive effect when the device is discharged into massed forces of the enemy.

In Fig. 5, I have shown a slightly different form of the device as illustrated in Fig. 4, wherein, in addition to the bombs 14 on the cable sections, a series of spaced pendant cables 17 are connected to each cable section 13, and to each of the pendant cables spaced bombs 18 are attached. In this 30 manner, I provide means for the attachment of a large number of explosive bombs on the connected balls or projectiles.

In Fig. 6 of the drawings, I have shown the device provided with means designed 35 for removing barbed wire obstructions commonly employed in trench warfare. To this end, the cable sections 13 connecting the spaced shot, are provided with a plurality of pendant drag hooks 19 of relatively different lengths. When the device is discharged at the trenches of the enemy, these hooks will engage the barbed wire obstructions, removing the same and carrying the wire into the ranks of the enemy so that 45 the men will become entangled therein. The efficacy of this form of the device will thus be apparent.

In Fig. 7 of the drawings, I have shown illuminating means carried by the connected projectiles, whereby the field of battle 50 may be illuminated. To this end, I suspend from each of the cables 13, a multiplicity of electric light bulbs indicated at 20, which are connected in series. The electric batteries 21 constitute the source of current and are connected by suitable wiring to the two series of bulbs. The circuit is, of course, closed prior to the discharge of the projectile from the gun barrel and, in 55 its flight over the field of battle, the large number of electric light bulbs serve to illuminate the field.

In Fig. 8 of the drawings, I have shown a different illuminating means, wherein 60 saturated felt, cotton or other suitable ma-

terial indicated at 22, is suitably fixed to each of the connecting cables 13. This material is saturated with kerosene, gasoline, or similar inflammable liquid. This form of the device may be employed with the desired effect in firing the ammunition stores of the enemy, or destroying flying machines, ammunition factories, and similar property necessary to the successful conduct of modern warfare.

In Fig. 9, I have shown still another means for providing a torch on the projectile, wherein a cylinder 23 is secured upon each of the connecting cables 13, the wall of the cylinder being perforated. Upon the cylinder, suitable porous fabric material 24 is secured. The balls connected by the cable sections are hollow to receive expandable bags or containers 25, and suitable flexible tubes 26 lead from these bags to the ends of the cylinders 23 and supply the latter with gas or oil contained in the bags. These bags are constructed of suitable elastic material which, by its compressive action, discharges the oil or gas continuously into the cylinders 23. This oil or gas, when ignited, causes the fabric 24 to blaze.

From the above description, taken in connection with the accompanying drawings, the construction and advantages of the several forms of my invention will be clearly and fully understood. In that form of the device wherein the centrally coiled section of the cable is employed, it will be seen that as this cable unwinds, it may be caused to assume any desired form by placing a greater charge in one of the gun barrels than in the other so that the shot will be projected at different speeds. This will be necessary when the device is fired at an irregular trench in order that all portions of the cable, throughout its length, and the terminal balls will reach the trench at the same time. My invention, as a whole, is exceedingly simple in its construction, highly reliable and effective in practical use, and may manifestly be produced in large quantities at comparatively small cost.

While I have above referred to the several preferred forms of my invention, it is to be understood that I also contemplate producing the device in various other constructions which may be found desirable in particular instances. I, therefore, reserve the privilege of making all such legitimate changes as may fairly fall within the spirit and scope of the invention as claimed.

Having thus fully described my invention, what I desire to claim and secure by Letters Patent is:—

1. A projectile of the character described including spaced members, and a flexible element having a coiled portion carried by one of said members, said element being connected to the remaining members.

2. A projectile of the character described including a series of projectiles proper, cable sections yieldably connected at their ends to said projectiles, and explosive bombs attached to each of the cable sections. 5
3. A projectile of the character described including a series of spaced projectiles proper, cables connecting the projectiles to each other, inflammable means carried by 10 each of the cables, and a combustible agent carried by each of said projectiles to be supplied to the inflammable means.
4. A projectile of the character described including a plurality of projectiles proper 15 each being hollow, a container in each projectile, said containers being adapted to contain a combustible fluid, cables connecting the projectiles to each other, a foraminated cylinder on each of said cables, an inflammable material secured upon each cylinder, and conduits to supply the combustible fluid from the projectiles to the interior of said 20 cylinders.
5. A projectile of the character described including a spaced series of projectiles proper, one of said projectiles being provided with a housing, and a cable having a coiled portion contained within said housing, the extremities of the cable being connected to the other projectiles. 25
6. A projectile of the character described including a plurality of projectiles proper, one of said projectiles being provided with a housing, a circular rotatable rod mounted within said housing, and a cable having a 30 double coil arranged upon said rod, the extremities of the cable being extended from the coils exteriorly of the housing and connected to the other projectiles.

In testimony whereof I hereunto affix my 40 signature in the presence of two witnesses.

DAVID GRIFFIN DOWNS.
